CLAIM

The ornamental design for a nail polishing pen, as shown and described.

DESCRIPTION

FIG. 1 is a front, right and bottom perspective view of a nail polishing pen, showing my new design;

FIG. 2 is a rear, left and top perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top plan view of the nail polishing pen of FIG. 1; and,

FIG. 8 is an enlarged bottom plan view of the nail polishing pen of FIG. 1.

The broken lines shown in the drawings illustrate portions of the nail polishing pen that form no part of the claimed design.

1 Claim, 8 Drawing Sheets
